RAILWAY SIGNALING APPARATUS

Henry S. Young, Wilkinsburg, Pa., assignor to
 The Union Switch & Signal Company, Swiss-
 vale, Pa., a corporation of Pennsylvania

Application November 21, 1941, Serial No. 419,850

6 Claims. (Cl. 246—41)

My invention relates to railway signaling apparatus, and is has particular reference to the organization of such apparatus into novel and improved forms of railway signal systems of the class involving searchlight signals.

Signal systems employing searchlight type signals usually utilize circuit controlling contacts operated by the operating mechanism of such signals for effecting control of other portions of the signal system, as for example, a searchlight signal governing traffic on a stretch may have contacts operated thereby interposed in the control of the signal next in the rear. Such signal mechanisms, which may for example be of the type shown in Letters Patent of the United States No. 2,172,724, granted on September 12, 1939, to Wesley B. Wells and William K. Lockhart for Light signals, usually are arranged in such manner that when the operating arm of the signal is in a position other than its stop position, and the operating winding is controlled to condition the operating arm to go to its stop position, a sticking or failure to open of the contacts operated by the signal mechanism cannot prevent movement of the operating arm to its stop position. Such a signal accordingly cannot be caused to display an improper indication due to its contacts sticking or freezing closed in a proceed position.

If, however, the contacts of a signal should stick closed in a proceed position, it is then possible that the rear signal may be caused to display a false indication due to the improperly closed contacts of the advance signal. I am aware that it has been proposed to check the operation of a searchlight signal by providing a relay, connected to the control system of a signal in multiple with the signal operating winding, and utilizing such relay to control the operating circuit of the rear signal. With such an arrangement, it might be possible for a signal to fail to clear due to an open circuit in its operating winding, and if a contact of such signal is stuck at clear, it would then be possible to have the rear or distant signal cleared with the advance signal displaying a stop indication.

In view of the foregoing and other important considerations, it is an object of my present invention to provide novel and improved means for checking the operation of contacts associated with searchlight type signals.

Another object is to provide novel and improved checking means for preventing false control of a device, such as a rear signal, should the

contacts of a searchlight signal fail to operate properly.

An additional object is to provide novel and improved signal systems involving searchlight type signals arranged in such manner as to avoid causing a rear signal to display an improper indication should the contacts of the advance signal fail to operate properly.

A further object is to provide novel and improved forms of railway signal systems of the type employing searchlight type signals.

The above mentioned and other important objects and characteristic features which will become readily apparent from the following description, are attained in accordance with my invention by providing, in conjunction with each searchlight type of signal, a pole changing relay and a stick relay. Each stick relay is normally energized over a stick circuit including its own front contact and controlled by traffic conditions in the section governed by the associated signal, and each stick relay is provided with a pick-up circuit completed when the contacts operated by the associated signal occupy their positions corresponding to a stop indication of such signal. Each pole changing relay is energized over a circuit including a front contact of the associated stick relay, and each pole changing relay functions to control the polarity of current supplied to the signal governing traffic in the block next in the rear.

I shall describe two forms of apparatus embodying my invention, and shall then point out the novel features thereof in claims.

In the accompanying drawing, Fig. 1 is a diagrammatic view showing one form of apparatus embodying my invention. Fig. 2 is a diagrammatic view representing a modified form of the apparatus shown in Fig. 1, and also embodying my invention. In each of the two views, similar reference characters have been employed to designate corresponding parts.

Referring to Fig. 1, the reference characters l and l_a designate the track rails of a stretch of railway track over which traffic normally moves in the direction indicated by an arrow or from left to right as viewed in the drawing. The rails l and l_a are divided by insulated joints 2 into a plurality of successive adjoining track sections, of which only one section, $D-E$, is represented complete in the drawing. Section $D-E$, as shown, is divided by insulated joints 2 at Da into subsections $D-Da$ and $Da-E$, each of which is provided with a track circuit comprising a suitable source of current, such as a battery 3 , con-

nected through an adjustable resistor 4 to the rails at one end of the associated subsection, and a track relay designated by the reference character TR with a suitably distinguishing suffix, connected to the rails at the opposite end of the subsection.

Each section has located adjacent its entrance end a signal, designated by the reference character S with a suitably distinguishing suffix, for governing traffic in the normal direction through the associated section. These signals, as mentioned heretofore, are of the searchlight signal type and each comprises an armature 8 mounted to rotate between an intermediate position, to which it is biased, and either of two extreme positions. Armature 8 is controlled by an operating winding 9 and is arranged in such manner that when the winding is deenergized, armature 8 assumes its biased intermediate position, when winding 9 is energized by current of what I shall term normal polarity, the armature rotates in a clockwise direction to its extreme left-hand position, and when winding 9 is energized by current of the opposite or reverse polarity, armature 8 is rotated in a counterclockwise direction to its extreme right-hand position. Attached to armature 8 to rotate therewith are colored roundels G, R and Y, which are arranged to be disposed in the path of a beam of light projected from an associated lamp 10 according as armature 8 occupies its extreme left-hand, its intermediate, or its extreme right-hand position, respectively. For convenience in illustration, the lamp 10 is represented in the drawing disposed above the associated roundels, but it will be readily understood that in actual practice lamp 10 will be located directly back of the associated roundels, and will have associated therewith a suitable optical system, not shown, for projecting a beam of light from the signal.

Each signal S indicates proceed, stop or caution according as roundel G, R or Y is in front of its associated lamp 10 when this lamp is lighted. Each signal S has operatively associated with its armature 8 a circuit controller comprising a plurality of movable contact fingers selectively operated into and out of engagement with a plurality of cooperating fixed or stationary contact fingers. For example, signal SD has two movable contact fingers 11 and 12, which engage back contact fingers 13 and 14, respectively, when armature 8 is in its biased intermediate position. When armature 8 is rotated to its left-hand position as shown in Fig. 1, contact finger 11 is operated out of engagement with member 13 and into engagement with member 15, and when armature 8 is rotated to its extreme right-hand position, contact finger 12 is operated out of engagement with member 14 and into engagement with member 16.

Each signal S is normally dark, and has its associated lamp 10 provided with an obvious energizing circuit including a source of current, such as a battery not shown but having its opposite terminals designated by the reference characters B and C, and a back contact 18 of a track relay of the section next in the rear of the section governed by such signal. The signals S are therefore approach lighted and caused to display an illuminated indication when the section in the rear is occupied.

Each signal S has associated therewith a checking relay, designated by the reference character CK with a suitably distinguishing suffix, normally energized over a stick circuit including

its own front contact 19 and completed over a front contact 20 of a track relay of the associated section, and provided with a pick-up circuit including, in series, contacts 12-14 and 11-13 of the circuit controller of the associated signal. The function of such a relay will be made clear in the following description.

Each signal S also has associated therewith a pole changing relay, designated by the reference character PCR with a suitably distinguishing suffix, for controlling the polarity of current supplied to the operating winding of the signal next in the rear. Relay PCR is energized over a circuit extending from terminal B through either contact 12-16, or contacts 12-14 and 11-15, of the circuit controller of the associated signal, front contact 21 of the associated checking relay CK, and the winding of relay PCR to terminal C.

Each signal S also is provided with an energizing line circuit controlled by traffic conditions in its associated section, by its associated checking relay CK, and by the pole changing relay PCR associated with the signal next in advance. The line circuit of signal SD, represented in Fig. 1, extends from terminal B through front contact 22 of relay PCR2 associated with the signal next in advance of signal SD, front contacts 23 and 24 of relays TR3 and TR2, respectively, operating winding 9 of signal SD, front contact 25 of relay TR2, front contact 26 of checking relay CK1, front contact 27 of relay TR3, and front contact 28 of relay PCR2 to terminal C.

When relay PCR2, associated with signal SE is released and the circuit of winding 9 of signal SD is closed at all other points, front contacts 22 and 28 of relay PCR2 open and the associated back contacts close to reverse the polarity of current supplied to such circuit, as is readily apparent from an inspection of the drawing.

In the normal condition of the apparatus, as represented in Fig. 1, section D-E and the sections in advance and in the rear are unoccupied; checking relay CK1 associated with signal SD is energized over its previously traced stick circuit; pole changing relay PCR1 associated with signal SD is energized over its previously traced circuit including, in series, contacts 12-14 and 11-15 operated by signal SD; pole changing relay PCR2 associated with signal SE is energized over circuit means not shown but substantially corresponding with those in detail for relay PCR1 associated with signal SD; and operating winding 9 of signal SD is energized by current of normal polarity with the result that armature 8 is in its extreme left-hand position to condition signal SD to display its proceed indication. Lamp 10 of signal SD is, however, deenergized and as a result signal SD is dark.

When a train occupies the section in the rear of section D-E, relay TR1 releases to close its back contact 18 and signal SD is caused to display an illuminated proceed indication until the train enters section D-E. When this happens, relay TR2 releases to open its front contact 20 and thereby open the stick circuit of relay CK1, which relay accordingly releases, and front contacts 24 and 25 of relay TR2 also open to open the energizing line circuit of signal SD, whereupon operating winding 9 becomes deenergized and signal SD is caused to display its illuminated stop aspect. The circuit of relay PCR1 accordingly is open due to the opening of contact 11-15 of signal SD and front contact 21 of relay CK1, whereupon relay PCR1 releases to reverse the polarity of current available to be supplied to the

line circuit for the signal associated with the section in the rear of section D—E. The line circuit of winding 9 of signal SD is also open at front contact 26 of relay CK1, but when contacts 12—14 and 11—13 close due to armature 8 of signal SD assuming its biased intermediate position, relay CK1 then becomes energized over its previously traced pick-up circuit, which includes the named contacts operated by signal SD, and relay CK1 accordingly closes its front contact 26 to prepare the line circuit of signal SD.

The line circuit of signal SD is further opened at front contacts 23 and 27 of relay TR3 when subsection Da—E is entered, and when the section in advance of section D—E is entered the polarity of current available to be supplied to this circuit is reversed when relay PCR2 is caused to release due to the associated signal SE being caused to assume its stop position, and the associated pole changing relay PCR2 being released.

When the train vacates the section in the rear of section D—E, relay TR1 picks up to open its back contact 18, thereby opening the illuminating circuit of lamp 10 of signal SD, whereupon that signal becomes dark. After the train vacates subsection D—Da, relay TR2 picks up to close its front contacts 24 and 25 to prepare the line circuit of winding 9 of signal SD, and front contact 20 of relay TR2 also closes to complete the stick circuit of relay CK1. Then, when the train vacates section Da—E, relay TR3 picks up to close its front contacts 23 and 27 to complete the line circuit for winding 9 of signal SD, and winding 9 is energized by current of reverse polarity to cause armature 8 to rotate to its right-hand position. Signal SD is accordingly conditioned to display its approach indication, and contact 12—16 of signal SD closes to cause relay PCR1 to pick up and close its front contacts to cause the current supplied to the line circuit of the section in the rear to be shifted from reverse to normal polarity.

When pole changing relay PCR2 is caused to pick up, the current supplied to the line circuit of signal SD is shifted from the reverse to the normal polarity and armature 8 of signal SD accordingly operates to its lefthand position to condition the signal to display its proceed indication. The apparatus associated with section D—E is thus restored to its normal condition as represented in the drawing.

Should, however, the contacts operated by signal SD fail to operate properly when the signal is conditioned to display its stop indication, such failure is detected by the associated apparatus in the following manner. Assume, for example, that with the apparatus in its normal condition as represented in the drawing, contact 11—15 fails to open when the train occupies section D—E and signal SD is conditioned to display its stop indication. In such an event, the stick circuit of checking relay CK1 is opened at front contact 20 of relay TR2 and relay CK1 accordingly releases. With contact 11—15 thus closed, the pick-up circuit of relay CK1 cannot become closed, and such relay remains released after the train vacates the section D—E and relays TR2 and TR3 pick up. With relay CK1 released, the line circuit of signal SD is opened at front contact 26, hence winding 9 of signal SD cannot be energized, and signal SD is caused to be conditioned to display its most restrictive or stop indication. In addition, relay PCR1 associated with signal SD remains released to cause the current supplied to the line circuit of the section in the rear of section D—E to be of

reverse polarity. This of course causes the signal in the rear of signal SD to be conditioned to display its approach indication.

From the foregoing, it is readily apparent that the apparatus embodying my invention is so arranged that when the contacts of a searchlight signal fail to operate properly, the signal is conditioned to display its most restrictive indication regardless of traffic conditions on the stretch, and the signal in the rear of such signal is conditioned to display its approach indication. It follows that should a signal operated contact be stuck in a clear position, and an open-circuit condition exist in the winding of such signal, the apparatus embodying my invention functions to prevent clearing of the signal, and it also controls the signal in the rear to display its approach indication, thus precluding the possibility of having a clear indication displayed by a signal in the rear of a signal displaying its stop indication.

In Fig. 2, the apparatus of Fig. 1 has been modified to incorporate approach lighting relays ATR, one for each track circuit and each connected in series with the track circuit source to the rails of the associated section. These approach lighting relays ATR are normally deenergized when the associated section is unoccupied, and are arranged in such manner that when a train occupies a section and establishes a train shunt across the track rails, the associated approach lighting relay ATR is effectively energized and picked up due to the increased current caused to flow in the track circuit. Each relay ATR when picked up closes its front contact 30 to complete an obvious energizing circuit for lamp 10 of the signal associated with the section in advance, and it follows that each signal S of Fig. 2 is caused to become approach energized when a train occupies the section in the rear of such signal.

In addition the apparatus of Fig. 2 is arranged with each pole changing relay PCR controlled over the line circuit for the signal in the rear. Relay PCR1 of Fig. 2, for example, is energized over a circuit extending from terminal B through front contact 31 of relay CK2, contact 32—33 or 34—35 of signal SE, the winding of relay PCR1, front contact 36 of relay TR2, contact 37—38 or 39—40 of signal SE, and front contact 41 of relay CK2 to terminal C. Relay PCR1 controls the polarity of current supplied to operating winding 9 of signal SD, as is readily apparent from an inspection of the drawing, and checking relay CK1 controls at its front contact 43 the supply of current to the associated signal SD.

It is believed that the operation of the apparatus of Fig. 2 will be readily apparent from an inspection of the drawing taken in connection with the foregoing description of the operation of the apparatus of Fig. 1, and a detailed explanation of the operation of the apparatus of Fig. 2 is believed unnecessary, it being noted that checking relay CK1 of Fig. 2 is released if the contacts operated by signal SD fail to operate properly and that when relay CK1 is released, signal SD is deenergized and is conditioned to display its stop indication, and the line circuit for the section in the rear is also deenergized so that the pole changing relay for the rear signal is deenergized, thus conditioning the rear signal to display its caution indication.

Although I have herein shown and described only two forms of railway signaling apparatus embodying my invention, it is understood that various changes and modifications may be made therein within the scope of the appended claims

without departing from the spirit and scope of my invention.

Having thus described my invention, what I claim is:

1. In a signaling system for a stretch of railway track divided into blocks each provided with a track circuit including a track relay, said system having for each block a signal provided with a controlling winding and arranged to indicate proceed or caution according as such signal controlling winding is supplied with current of one relative polarity or the other and indicating stop when such signal controlling winding is deenergized, each said signal controlling contacts selectively closed when such signal is conditioned to display proceed, caution, or stop, respectively; the combination with each of said signals of a stick relay normally energized over a stick circuit including its own front contact and controlled by the track relay of the associated block and provided with a pick-up circuit completed when the contacts of the associated signal occupy the positions corresponding to the stop indication of such signal, a pole changing relay associated with each signal and energized over a circuit including a front contact of the associated stick relay, and means controlled by each pole changing relay for controlling the polarity of current supplied to the signal of the block next in the rear.

2. In a signaling system for a stretch of railway track divided into blocks each provided with a track circuit including a track relay, said system including a line circuit for each block controlled by the track relay for such block and a signal for each block having a controlling winding supplied with current of one relative polarity or the other according as the associated line circuit is supplied with current of said one relative polarity or the other, each said signal being arranged to indicate proceed or caution according as such signal controlling winding is energized by current of said one relative polarity or the other and each signal displaying stop when its controlling winding is deenergized, each said signal being operatively connected with contacts selectively closed according as such signal is conditioned to indicate proceed, caution or stop, respectively; the combination with each said signal of a stick relay normally energized over a stick circuit controlled by the track relay of the associated block and provided with a pick-up circuit completed when the contacts of the associated signal occupy the positions corresponding to the stop indication of such signal, and means controlled by each said stick relay for controlling the polarity of current supplied to the line circuit of the block next in the rear.

3. In a signaling system for a stretch of railway track divided into sections each provided with a track circuit including a normally energized track relay, said system comprising a line circuit for each section including a front contact of the track relay for the associated section, and a signal for each section having a control winding supplied with current of one relative polarity or the other according as the line circuit for the associated section is supplied with current of one relative polarity or the other, each said signal being conditioned to display a first indication or a second indication according as the associated control winding is energized by current of one relative polarity or the other and displaying a third indication when such control winding is deenergized, each said signal having contacts operatively associated therewith and

selectively closed according as said signal is conditioned to display its first, second or third indication, respectively; the combination in such a system of a stick relay for each of said signals, a stick circuit for each stick relay including a front contact of such relay and a front contact of the track relay of the associated section, a pick-up circuit for each stick relay completed when the contacts of the associated signal occupy the positions corresponding to the said third indication of such signal, and means controlled by each stick relay for controlling the polarity of current supplied to the line circuit of the section next in the rear.

4. In a signal system for a stretch of railway track divided into a plurality of successive adjoining track sections each provided with a track circuit including a normally energized track relay, said system including a signal for each section having a control winding and arranged to display a first indication or a second indication according as said winding is energized by current of one relative polarity or the other and displaying a third indication when said winding is deenergized, each said signal having contacts operatively connected therewith and arranged to be selectively closed according as the associated signal displays its first, second or third indication, respectively; the combination in such a system of a stick relay for each of said signals, a stick circuit for normally energizing each of said stick relays and including a front contact of such relay and a front contact of the track relay of the section associated with the associated signal, a pick-up circuit for each stick relay completed when the contacts of the associated signal occupy the positions corresponding to the said third indication of said signal, and a circuit including a front contact of a stick relay for supplying energy of one relative polarity or the other to the control winding of the associated signal according as the signal in advance is displaying either its said first or second indication or said advance signal is displaying its said third indication.

5. In a signal system for a stretch of railway track divided into a plurality of successive adjoining track sections each provided with a track circuit including a normally energized track relay, said system including a plurality of signals one for governing traffic in each of said sections, each of said signals having a control winding and an operating member operated thereby from a biased intermediate position to one or another of two extreme positions according as said control winding is energized by current of one relative polarity or the other, each said signal having contacts operatively connected with its operating member in such manner as to be selectively closed in the three positions of said member; the combination in such a system of a plurality of stick relays one for each of said signals and each normally energized over a stick circuit including its own front contact and a front contact of the track relay of the section governed by the associated signal, a plurality of pick-up circuits one for each of said stick relays and each completed when and only when the contacts operated by the associated signal occupy the positions corresponding to the biased intermediate position of the operating member of such signal, and a plurality of energizing circuits one for each signal and each including a front contact of the associated stick relay and including means governed by the signal in advance for controlling the polarity of current supplied to such circuit.

6. In combination with a section of railway track provided with a track circuit including a track relay and having associated therewith a signal for governing traffic in said section and comprising a control winding and an operating member operated by said control winding from a biased intermediate position to one or another of two extreme positions according as said control winding is energized by current of one relative polarity or the other, said signal having contacts operatively connected with said operating member and selectively closed in each of the three positions of said operating member, a

stick relay normally energized over a stick circuit including its own front contact and a front contact of said track relay, a pick-up circuit for said stick relay completed when and only when 5 the contacts of said signal occupy the position corresponding to the biased intermediate position of said operating member, and means controlled by said track relay and including a front contact of said stick relay for energizing said control winding with current having one relative polarity or the other in accordance with traffic conditions in advance of said section.

HENRY S. YOUNG.
